UNITED STATES PATENT OFFICE

THOMAS J. PERRIN, OF BROOKLYN, NEW YORK.

TELEPHONE SWITCH-BOARD.

SPECIFICATION forming part of Letters Patent No. 280,663, dated July 3, 1883.

Application filed December 22, 1882. (No model.)

To all whom it may concern:

Be it known that I, THOMAS J. PERRIN, a citizen of the United States, residing at Brooklyn, in the county of Kings and State of New York, have invented new and useful Improvements in Telephonic Switch-Boards, of which the following is a specification.

This invention relates to that class of telegraphic and telephonic switch-boards which are provided with metallic line-terminal plates arranged for connection by plugs. Its objects are to facilitate the connection of two loop-circuits, or of the four separate lines which compose two two-wire circuits, and to enable the ready exchange of signals between a central office and stations upon such circuits.

In carrying out my invention I place upon a switch-board a plurality of metallic terminal plates for each line-wire or loop branch, and so arrange these plates in pairs that a pair representing terminals of the two wires of any two-wire circuit or terminals of the two branches of any loop-circuit will be in close proximity to and adapted for plug-connection with a similar pair of terminals of every other such circuit centering at the switch-board. I also provide such board with a separate section composed of pairs of "calling-plates" representing each loop or two-wire circuit, and arrange these pairs of calling-plates in such relation to a plurality of pairs of terminal plates of a signaling-circuit that by the simple insertion of a proper plug-connection any loop or two-wire circuit is placed in a complete metallic circuit including the central-office signaling-instruments. I further provide each switch-board with a listening-telephone circuit having terminal plates arranged in such relation to the line-terminal plates that by the insertion of a proper plug the listening-telephone may be connected with any line-circuit in proper manner to enable articulate communications to be heard at the central office.

In order that my invention may be fully understood, I will proceed to give a particular description of a switch-board embodying the same, referring to the accompanying drawings, in which—

Figure 1 is a front elevation of a switch-board having circuits and terminal plates arranged according to my invention. Fig. 2 is a section of the board on line xx of Fig. 1. Fig.

3 is a perspective view of a double plug-connector used in connecting the pair of plates.

The letter A designates the switch-board. 55

The line-terminal plates are indicated by 1^a 1^b 2^a 2^b, and so on. In the present instance there are eight distinct loop-circuits connected with the board, and each loop wire or branch is provided with four terminal plates. For 60 instance, the two wires which compose loop-circuit "one" at the left are connected to the binding-posts 1 and 1', respectively. The post 1 is connected, as shown by dotted lines, with all the plates marked 1^a, and the post 1' is 65 similarly connected with all the plates marked 1^b. The posts 2 and 2' are in like manner connected with the plates 2^a and 2^b, and so on. It will be seen that in the two upper rows of plates a pair of plates of the first loop is followed by a pair of the second loop, and these by a pair of the third loop, after which comes again a pair of the first loop, and then pairs of the fourth and fifth loops in similar order. Then again, a pair of the first loop is followed by pairs of the sixth and seventh loops, and, finally, the last pair of the first loop is followed by a pair of the eighth loop. It will be observed that a pair of terminal plates of the first loop is thus brought adjacent to a pair 70 of terminal plates of every other loop connected to the board. Now, in the second two rows of plates there are pairs of the second loop directly under the pairs of the first loop, and pairs of the other loops intermediately arranged in order, as in the first two rows. In the third two rows, pairs of the third loop are directly under pairs of the second loop, and so on for all the rows in a similar manner, which will now be readily understood. In the rows 75 of plates following the first two rows, spaces are left vacant at the right-hand ends of the rows, because a sufficient number of pairs of plates have been used without filling these spaces, and thus an aggregate space is left in 80 which rows of plates for other circuits may be arranged without following the vertical serial order—as, for instance, after the pairs of the fifth loop have been arranged in the vertical series the pairs of the sixth loop are commenced 85 at the right and followed to the left by other pairs in order, and over the rows devoted to the sixth loop the pairs of the seventh loop are placed, followed at the left by a pair of the 90

100

eighth loop, which completes the arrangement of the pairs of terminal plates of all the loops, so that any loop has a pair of plates adjacent to a pair of every other loop.

- 5 The connecting-plug P is composed of two pairs, p and p', of metal spring-fingers, connected to an insulating-bar, I, the fingers of each pair being electrically connected. Now, suppose it is desired to connect two of the 10 loops—say loop "one" and loop "six"—together in metallic circuit. This is done by inserting the plug P, as shown, so that one pair of the fingers will be between plates 1^a and 6^a and the other pair will be between plates 1^b and 15 6^b. The connection will then be complete, as follows: Say from post 1 through the first three plates 1^a and their connecting-wires, over the adjacent fingers of the plug to plate 6^a, thence to post 6 over the loop "six" and 20 back to post 6', and thence to plate 6^b over the plug-fingers to plate 1^b, and thence to post 1' and over loop "one" back to post 1. The connections between the plates mentioned in this 25 illustration are shown in dotted or broken lines; but the connections between the line-terminal plates generally are omitted from the drawings to avoid confusion. They will be, however, readily understood from the explanations which have been given.
- 30 The "calling-section" of the board is designated by the letter M. This section is composed of two rows of terminal plates arranged in pairs. Five of these pairs are each composed of plates marked C and C', and between 35 each two of these pairs are interposed two pairs of line-plates. For instance, after the first pair of plates marked C C' at the left comes a pair marked 1^a 1^b, followed by a pair marked 2^a 2^b, and then another pair marked 40 C C', followed by pairs marked 3^a 3^b and 4^a 4^b, and so on. The plate marked 1^a is connected with the post 1 either directly or through line-plates 1^a, and the plate marked 1^b is connected with post 1', so that these two 45 plates form a pair of terminals for loop "one," and are termed its "calling-plates." The other numbered plates in these two rows are similarly connected with loops having similar numbers. The plates marked C are all connected together electrically and with the anvil of a key, K, as indicated by broken lines, and the key is connected with a circuit-breaking wheel, W, having four "breaks," w, of insulating material, so that the periphery of 55 the wheel is composed of alternating conducting and non-conducting spaces. Upon the periphery of this wheel rests the free end of a metallic contact-arm, N, having its other end connected with one pole of a signaling-battery, B, the other pole of which is connected with all of the plates marked C', as indicated by broken lines. If, now, the operator at the central office desires to call a subscriber or station on loop "one," he inserts plug P, as 60 shown, so that two of its fingers connect plate 1^a with a plate, C, and its other two fingers connect plate 1^b with plate C'. He then de-

presses key K and turns the break-wheel W, and the making and breaking of the battery-circuit will cause the operation of a signal apparatus included in loop "one," for it will be seen that each time a conducting portion of W passes under the arm N a circuit is completed from post 1 to plate 1^a over the plug-fingers to plate C, thence over the other plates C, the 70 key and connections to the break-wheel, through the wheel and contact-arm N to one pole of the battery, and from the other battery-pole over the plates C' and intermediate connections to the plug, and over the plug to 75 plate 1^b, and thence to post 1' and over the loop back to post 1.

A small bell, Q, is connected in the battery-circuit at the central office, and will ring while a call is being made. The call may be 80 answered by the called subscriber or operator by simply breaking circuit, as then, of course, the bell Q will cease to ring, and its cessation will indicate to the calling operator that the called subscriber or operator has received the 85 call. Signaling or calling over the other loops may be performed in a similar manner.

At the left-hand end of the calling-section is a pair of plates, marked T T', which are connected with a telephone, R. By connecting this pair of plates with the adjacent pair C C' the telephone is placed in a derived circuit with the loop which has been plugged for signaling, and oral communication may thus be had between the calling operator and 90 the one called.

Instead of the break-wheel, I may use any other kind of automatic circuit-breaker, and may also use any other kind of electric generator than a battery. The battery or generator 105 may also be grounded and a single line-wire used for calling purposes, or two separate line-wires, one being to ground direct and the other to ground through the battery, in the manner now well known in electrical circuiting.

At the left of each two rows of line-terminal plates in the switch-board is a pair of plates marked G L. The plates G are all electrically connected together and to ground, and the plates L are all connected electrically together 115 and to ground through a listening-telephone, R'. It is obvious that if a plug be inserted between any pair of plates G L and an adjacent pair of line-plates, one end of the loop which the line-plates represent will be connected to ground through plates G and the other end to ground through the plates L and telephone R', and the operator may thus converse with the subscriber on the loop; or, if the loop be connected with another, the listening-telephone will be in a derived or branch circuit with the two connected loops, and the listening operator may thus ascertain at any time whether or not communication between any two subscribers has been finished.

At the right of the board I show simply a long plate, L', which is electrically connected with the plates L, forming a continuation electrically of the plates L to such position as will

readily enable connection to be made between the circuit of L and the circuits represented by the terminals upon the right of the board. By connecting the plate L' with any adjacent pair of plates by means of the plug, the telephone R is brought into a branch circuit, and over it may be heard any communication going on over the loop represented by the pair of plates and a loop connected therewith.

10 It is obvious that the switch-board as now described is quite as applicable for use with two-wire circuits as with loop-circuits, as all that is necessary to change a loop to a two-wire circuit is that the subscriber shall break his loop and connect the branches or resulting two lines to ground.

I wish it to be understood that although I have illustrated in my drawings an arrangement of line-terminal plates which I prefer, I do not confine myself to such arrangement, as it is only necessary that each loop or two-wire circuit shall have a pair of terminal plates adjacent to and adapted for plug-connection with a pair of terminal plates of every other similar circuit centering at the board.

25 Having thus described my invention, what I claim is—

1. A switch-board having a number of terminal plates for each line-wire equal to half the total number of wires to be connected, each line-wire having its own section or row on the board, and its terminal plates so alternated therein with terminal plates of the succeeding wires that plug-connection may be made with 30 any other wire, substantially as described.

2. A switch-board having a number of terminal plates arranged in pairs for loop or complete metallic circuits, the number of pairs being equal to half the number of such circuits, the pairs of any one such circuit being so alternated or arranged relatively to the pairs of every other circuit that plug-connection from the plates of any one circuit may be made to a pair of plates of any other circuit, substantially as described.

3. In a switch-board having its terminal plates arranged as hereinbefore set forth, the combination, with the terminal plates representing the various circuits, of terminal plates connected with a listening-telephone circuit, whereby such listening-telephone circuit may be connected to any service-circuit, substantially as described.

4. In a switch-board for a loop or two-wire circuits, the combination, with the line terminals, of the calling-section having a pair of line-terminal or plug plates for each circuit, and a plurality of pairs of plates representing a signal-circuit, a pair of the signal-circuit plates being arranged for plug-connection with each pair of line-plates, substantially as described.

5. The combination, with the pairs of calling-section plates, of the pair of plates arranged for connection with a telephone, substantially as described.

6. The combination, with the pairs of connected calling-section plates C C' and the intermediate line-plates connected therewith, of an automatic circuit-breaker and electric generator connected with said plates C C', substantially as described.

7. In a switch-board for a central telephone or telegraph office or exchange, a number of rows of contact-plates, the first and thereafter every third plate in each row forming a terminal of the line to which the row is assigned, the intervening plates being terminals of the succeeding lines, so that circuit may be made from the line assigned to the row to every other line, substantially as described.

In testimony whereof I have hereunto set my hand in the presence of two subscribing witnesses.

THOMAS J. PERRIN.
